UNITED STATES PATENT OFFICE.

JOHN T. MEATS, OF TAUNTON, MASSACHUSETTS; ANNE ELIZABETH MEATS AND JAMES E. GREENSMITH, EXECUTORS OF SAID JOHN T. MEATS, DECEASED, ASSIGNORS TO MASON MACHINE WORKS, OF TAUNTON, MASSACHUSETTS, A CORPORATION OF MASSACHUSETTS.

THREAD-GUIDE SUPPORT FOR SPINNING OR TWISTING FRAMES.

No. 904,493.

Specification of Letters Patent.

Patented Nov. 17, 1908.

Application filed October 20, 1906. Serial No. 339,777.

To all whom it may concern:

Be it known that I, JOHN T. MEATS, a citizen of the United States, and resident of Taunton, county of Bristol, State of Massachusetts, have invented an Improvement in Thread-Guide Supports for Spinning or Twisting Frames, of which the following description, in connection with the accompanying drawing, is a specification, like letters on the drawing representing like parts.

This invention relates to spinning or twisting frames, and has more especial reference to the thread or yarn guide and the supporting means therefor.

In the practical embodiment of my invention hereinafter fully described in the specification and particularly pointed out in the following claims, taken in connection with the accompanying drawings, the thread-guide support is made wholly of metal, and certain features of my invention have been more particularly designed to meet the demand for fine and accurate adjustment, in all directions, of the thread-guide.

Heretofore, in the case of the old wooden thread-board, so-called, the thread-guide screwed into the wood and adjustment was obtainable only to a limited extent, and that in one direction, while in the case of the metallic thread-guide supports now made adjustment of the guide can be had in two directions only.

In my present invention I have made the thread-guide adjustable laterally, fore and aft, and radially, the latter adjustment being very valuable, particularly in fine work, in the case of thread-guides which have depending kink-arresters, and so far as I am aware this adjustment is not obtainable with the guide-supporting devices as now made.

In the practical embodiment of my invention selected by me for illustration and explanation herein, Figure 1 of the drawing is a side elevation of the thread-guide and support therefor, partly broken out, the fixed part of the frame on which the support is mounted being shown in section, and I have shown in dotted lines two positions of some of the parts; Fig. 2 is a front elevation of one of the brackets by which the finger-head rail or support is connected with its hinges; Fig. 3 is a top plan view of the bracket; Fig. 4 is a front elevation of the

metallic finger-head forming a part of my invention; Fig. 5 is a top plan view thereof; Fig. 6 is a top plan view of the hinge member connecting the finger-head and the finger-head rail, and Fig. 7 is a front elevation thereof; Fig. 8 is a perspective view of one of the rail-sustaining hinges.

Referring to Fig. 1 a fixed portion of the frame of a spinning or twisting machine commonly termed the roller-beam is indicated at A, and thereto is pivotally connected the finger-head rail or support, herein shown as an angle iron, 1, and by reference to Fig. 1 it will be seen that it is L-shaped in cross-section, with its depending flange at the front, the rail extending longitudinally of the frame and of suitable length.

A plurality of hinges, such for instance as separately illustrated in Fig. 8, are secured to the roller-beam by screw-bolts 2, Fig. 1, extended through slots 3 in the leaves 4 of the hinges, so that the latter may be adjusted vertically. The shorter free leaves 5 of the said hinges are secured by suitable fastenings 6 to the bodies 7 of metallic brackets, shown separately in Figs. 2 and 3, one of such brackets being secured to each of the hinges.

Herein I have shown each bracket body as provided with three forward extensions or bosses 8 perforated at 9 to receive screw studs or other suitable fastenings 10, by which the brackets are rigidly attached to the web of the finger-head rail 1, as clearly shown in Fig. 1. Said rail is thus pivotally connected or hinged to the roller-beam A, and can be swung up into dotted line position at 1° for doffing.

In order to maintain the rail in its operative horizontal position I have formed each bracket with a depending and rearwardly turned extension 11 adapted to bear 95 against the fixed leaf 4 of its adjacent hinge, (as in full lines Fig. 1) the extension serving as a stop to limit descending movement of the rail and maintain it in its operative position.

The thread-guides are mounted on finger-heads, one for each, and a series of such finger-heads are pivotally connected with the rail.

In accordance with my present invention 105 I make the finger-head of sheet-metal,

stamped or pressed into shape to present a flat top 12, a depending front portion 13 having an elongated transverse aperture or slot 14 therein, Fig. 4, and downturned 5 stiffening portions 15 extending from the side edges of the portion 13 toward the back of the finger-head and decreasing in depth, so that the stiffening portions are substantially triangular in shape. The finger-head 10 so made is light, strong and durable, and presents no portions for the collection of lint, fly, etc.

At the rear edge the finger-head is bent or rolled over to form a tubular hinge-pin 15 socket 16, see dotted lines Fig. 5, centrally located with relation to the sides of the finger-head and of such length that a clearance is left at each end, for a purpose to be described.

20 I connect the finger-heads and rail by sheet-metal hinge members, shown separately in Figs. 6 and 7, each member having a flat body 17 rearwardly turned at its lower edge to form a guide foot 18, which projects beneath the edge of the flange of the rail 1, the body being attached to the face of the flange by suitable screws 19, Fig. 1.

The central portion of the body is slotted downward from its upper edge and the intervening portion of the metal is bent forward and upward, as at 20, to form a stop or support for the finger-head, to retain it in its operative position, as shown in full lines Fig. 1. At each side of the stop 20 35 the metal of the body 17 is bent or rolled over to form two pin sockets 21 in alignment, and separated by a distance slightly greater than the length of the socket 16 on the finger-head, so that the latter socket will fit 40 easily in the vacant space.

A hinge-pin 22 passed through the sockets pivotally connects the finger-head and hinge member, and through the latter the finger-head is connected with the rail 1.

45 The pin 22 may extend the length of the rail, cooperating with all the finger-heads thereon, or a separate pin may be used for each head, as desired or found most convenient.

50 The operative position of the rail and finger-heads is shown in full lines Fig. 1, and when the rail is swung up for doffing all the finger-heads will be swung up in unison, but any one of the finger-heads can be 55 swung upward on the pin 22 as a fulcrum, as shown by dotted lines at 12*, Fig. 1.

I have herein shown the thread-guide as a piece of stout wire bent to form a guide-eye 23, a depending kink-arrester 24, and an 60 elongated, straight, cylindrical shank 25, screw-threaded for a portion of its length, the shank being of such diameter that it will pass loosely through the slot 14 of the finger-head.

65 Two clamping-nuts 26 are employed to hold

the thread-guide securely and rigidly in position, said nuts engaging the threaded portion of the shank and being set up against the opposite faces of the depending portion 13 of the finger-head, as shown in Fig. 1.

70 By loosening one of the nuts the shank can be moved laterally in the slot to adjust the thread-guide longitudinally of the frame, and when the nuts are again set up the guide is rigidly clamped in such adjusted position.

75 By setting up one nut and easing off the other the guide is adjusted in a fore and aft direction, or longitudinally of its shank, and of course there can be a combination of such adjustment with the lateral adjustment described.

80 If a radial or angular adjustment is required the thread-guide is turned on its shank as a center in one or the other direction, to give any desired angle or position to the eye and the kink-arrester, the nuts when set up holding the adjustment.

85 Any or all of the adjustments of the thread-guide can be made very finely or accurately, and all adjustments are held by the common clamping means.

90 The nuts 26 are herein shown as made deep by extensions 27 which are counter-bored at 28 (see full and dotted lines Fig. 1) the counterbored portions inclosing the threaded part of the guide shank and preventing the accumulation of fly thereupon.

95 As will be manifest the entire structure of the thread-guide support is made of metal, and is light, strong, durable and of simple 100 construction.

105 Various changes may be made by those skilled in the art in different details of my invention without departing from the spirit and scope thereof.

Having fully described my invention, what I claim as new and desire to secure by Letters Patent is:—

1. In a device of the class described, a sheet-metal finger-head having downturned 110 integral side and front portions, the front portion having an elongated lateral slot, combined with a thread-guide having a cylindrical shank adapted to extend loosely through the slot and bodily adjustable laterally parallel to the slotted portion and in and out with relation to the finger-head, and means to engage directly the shank and opposite faces of the slotted front portion of the finger-head, to clamp the thread-guide 115 in adjusted position thereon.

120 2. In a device of the class described, a sheet-metal finger-head having downturned integral side and front portions, the front portion having an elongated lateral slot, 125 combined with a thread-guide having an elongated cylindrical shank threaded for a portion of its length and adapted to extend loosely through the slot, to be adjusted therein, and clamping nuts engaging the 130

threaded portion on opposite sides of the slotted portion of the finger-head and counterbored to inclose the threads on the shank, the nuts rigidly securing the thread-guide in 5 adjusted position on the finger-head and at right angles to the slotted portion thereof.

3. In a device of the class described, a finger-head, a thread-guide carried thereby and adjustable angularly, laterally and fore 10 and aft with relation thereto, and means to secure the thread-guide in adjusted position, said securing means being common to all of the specified adjustments.

4. In a device of the class described, a finger-head, a thread-guide carried thereby and adjustable angularly and laterally with relation thereto, the laterally adjusted positions of the thread-guide being in parallelism to each other, and means to secure the 20 thread-guide in adjusted position.

5. In a device of the class described, a sheet-metal finger-head having a downturned front portion provided with a lateral slot, a thread-guide having a cylindrical 25 shank extended through the slot at right angles to the slotted portion, said shank being longitudinally, laterally and angularly adjustable in the slot, and means to engage the slotted portion of the finger-head and 30 clamp the shank thereto in adjusted position.

6. In a device of the class described, a sheet-metal finger-head having a downturned front portion provided with an elongated aperture, a thread-guide having a 35 threaded cylindrical shank loosely extended through the aperture, and laterally movable therein, and clamping nuts on the threaded portion of the shank to bear against the opposite faces of the apertured portion of the 40 finger-head, to clamp such portion between them and secure the thread-guide in adjusted position thereon.

7. In a device of the class described, a sheet-metal finger-head having a downturned front portion provided with an aperture, a thread-guide having a threaded shank loosely extended through the aperture, and clamping nuts on the threaded portion of the shank to bear against the opposite 50 faces of the apertured portion of the finger-head, to secure the thread-guide in adjusted position thereon, the nuts having tubular extensions to cover the thread of the shank and prevent the accumulation of foreign matter 55 thereon.

8. In a device of the class described, a sheet-metal finger-head having a downturned front portion provided with an elongated aperture, a thread-guide having a 60 cylindrical shank extended loosely through and laterally movable in the aperture, and means to clamp the shank in adjusted position on and to directly engage the apertured portion of the finger-head.

65 9. In a device of the class described, a

sheet-metal finger-head having an integral downturned front portion provided with an elongated transverse slot, a thread-guide having a shank adapted to extend loosely through the slot and bodily adjustable 70 therein laterally of the finger-head, and means to engage the slotted portion and clamp the thread-guide in adjusted position on the finger-head.

10. A sheet-metal finger-head having an 75 integral downturned front portion provided with an aperture, and stiffening portions extending rearwardly from the side edges of said apertured portion and decreasing in depth toward the back of the finger-head, a 80 thread-guide having a shank extended through the aperture, and clamping nuts on the shank and adapted to bear upon opposite faces of the depending apertured front portion of the finger-head. 85

11. A finger-head made of sheet-metal bent to present a flat top portion, a deep depending front portion, and triangular downturned stiffening portions extending rearwardly from the side edges of the front portion, a thread-guide, and means to wholly support and secure it rigidly on the downturned front portion of the finger-head. 90

12. In a thread-guide support for spinning or twisting frames, an L-shaped, 95 metallic finger-head rail, pivotally supported at its rear edge, a hinge having pin sockets at its upper end and a rearwardly turned foot, secured to the depending flange of the rail, the foot of the hinge passing under the flange, a finger-head having a pin socket adapted to enter between the pin sockets of the hinge, to receive the hinge-pin and pivotally connect the finger-head and hinge, and a stop on one coöperate with the 100 other of said members and support the finger-head in operative position. 105

13. In a thread-guide support for spinning or twisting frames, an L-shaped, 110 metallic finger-head rail, fixedly mounted hinges, brackets rigidly secured to the web of the rail and to the movable leaves of the hinges, to connect the rail and hinges, a depending extension on each bracket to engage a fixed part of the frame and sustain the 115 rail in horizontal position, a plurality of finger-heads pivotally connected with the flange of the rail, and stops to maintain the finger-heads in operative position with relation to the rail. 120

14. In a thread-guide support for spinning or twisting frames, an L-shaped, 125 metallic finger-head rail, a plurality of brackets rigidly attached to the under side of the web of the rail, rail-supporting hinges having their movable leaves secured to the brackets at right angles to the web of the rail, a depending, rearwardly turned extension on each bracket to bear against a fixed part of the frame and support the rail 130

in horizontal position, and finger-heads pivotally connected with the flange of the rail.

15. In a thread-guide support for spinning or twisting frames, an L-shaped, metallic finger-head rail, a plurality of brackets rigidly attached to the under side of the web of the rail, rail-supporting hinges having short leaves secured to the brackets 5 at right angles to the web of the rail, and long leaves adapted to be secured to a fixed 10 part of the frame in vertical position, and

a depending, rearwardly turned extension on each bracket to bear against the fixed leaf of the connected hinge and maintain 15 the rail in horizontal position.

In testimony whereof, I have signed my name to this specification, in the presence of two subscribing witnesses.

JOHN T. MEATS.
